UNITED STATES PATENT OFFICE.

FRANK M. FABER, OF CANTON, OHIO.

PNEUMATIC HAMMER.

1,205,607.

Specification of Letters Patent. Patented Nov. 21, 1916.

Application filed September 2, 1915. Serial No. 48,614.

To all whom it may concern:

Be it known that I, FRANK M. FABER, a citizen of the United States, residing at Canton, in the county of Stark and State of Ohio, have invented certain new and useful Improvements in Pneumatic Hammers, of which the following is a specification.

The invention relates to hammers of the pneumatic type, of the kind which includes a cylinder containing a cylindric valve block, a piston therein, and a sliding cylindric valve on the block for controlling the operation of the piston; and the objects of the invention are to provide a valve which will be perfectly stable in all positions of the piston, to prevent the leakage of fluid between the valve and adjoining parts from interfering with the operation of the valve and piston, and to arrange the longitudinal ports in the cylinder so that the bore thereof can be sized from time to time. These objects, and other advantages, are attained by the preferred embodiment of the invention illustrated in the accompanying drawings forming part hereof, in which—

Figure 1 is a vertical sectional view of part of the improved hammer; Fig. 2 is a horizontal sectional view showing the entire cylinder with a nut or cap thereon; Figs. 3, 4, 5, 6, 7, 8 and 9 are sectional views on the planes A—A, B—B, C—C, D—D and E—E, Fig. 2, and F—F and G—G, Fig. 1, respectively, with the cylinder removed; Fig. 10 is a fragmentary enlarged sectional view 35 of Fig. 2 on the plane A—A; Fig. 11 is a fragmentary enlarged sectional view on the plane H—H, Fig. 3; and Fig. 12 is a sectional view on the plane N—N, Fig. 1.

1 is the handle of the hammer.
2 is the main admission port which communicates with a throttle valve operated by a thumb lever in the usual manner, which is not shown in the drawing.

3 is an annular chamber in the handle, 45 communicating with the main admission port 2.

4 is a cylindrical chamber in the handle, 50 7 is the valve block, 13 the valve, 31 the cylinder, 32 the cylinder bore.

32 is a piston, having a close sliding fit in the cylinder bore 32, and also in the interior of the valve block 7.

33 is the snap or rivet set. For convenience, I will refer to that part 55 of the hammer on the left of the drawings, as the forward end, and that toward the right as the rear end of my device.

The interior of the valve thimble 7 has the diameter L, which is equal to—or may 60 be slightly larger than the cylinder bore. The valve thimble closely fits the valve block on diameter H.

10 is an internal annular groove in the valve thimble.

8 is a series of ports in the valve thimble which communicate with the annular chamber 3 in the handle and with the internal annular groove 10 in the thimble.

52 and 54 are a series of radial holes from the outside to the inside of the thimble, which are arranged in pairs longitudinally of the thimble; each pair being connected together at the periphery of the thimble by a longitudinal narrow slot 51.

54 is an annular groove on the interior of the thimble, which registers with the series of holes 54.

51 is a counterbore on the end of the thimble.

The outside of the valve block 7 is finished to four coaxial diameters, H, I, J and K. The inside of the valve block, which is of the same diameter as the cylinder bore, forms a continuation thereof, and is held in exact alinement therewith by the close fit of diameter K of the valve block in the recess 28 in the cylinder.

6 is a series of ports in the valve block which communicate with the annular chamber 3 and thence with ports 8 in the valve thimble. Longitudinal ports 9 in the valve block are held in register with the similar ports 6 in the valve thimble by the dowel pin 5.

6^a is a port connecting one of the ports 6 with the cylinder bore.

16 are radial ports which lead from the ports 9 to the periphery of the valve block.

21 is a longitudinal port in the valve block; 20 a port leading from 21 to the periphery of the valve block.

21^a is a port in the cylinder which registers with port 21 and communicates with the cylinder bore at 30.

38 is an annular groove on the outside.

of the valve block; 36 a series of annular ports in the valve block which open into the groove 38 through the radial ports 37.

36^a are rearward continuations of the 5 ports 36 and communicate with the periphery of the valve block through the radial ports 40.

35 is a series of longitudinal ports in the cylinder which register with ports 36 in the 10 valve block and which enter the bore in the cylinder at 34. Ports 21 and 36 are held in register with ports 21^a and 35, respectively, by means of the dowel pin 41.

24 is an annular groove in the periphery 15 of the valve block which communicates with the interior of the block through the series of ports 25.

The handle and cylinder are secured together by means of the threaded parts 58; 20 the threads also perform the function of forcing the handle against the thimble at the neatly finished surface 1^b and also of forcing the thimble against the valve block at the neatly finished surfaces 7^c and also of 25 forcing the valve block against the cylinder at the neatly finished surfaces 29. The fits at the surfaces 1^b, 7^c and 29, are sufficiently close to prevent leakage.

The interior of the valve 13 is formed to 30 four coaxial diameters which make close sliding fits on the various outside diameters, H, I, J and K of the valve block; while the end periphery of the valve toward the right makes a close sliding fit in the diameter M in 35 the valve thimble.

56 is an annular groove on the interior of the valve, 57 is an annular groove on the periphery of the valve, and 55 are a series of small radial ports connecting the grooves 56 40 and 57.

48 is an annular groove on the interior of the valve, and 47 is a series of radial ports through the wall of the valve and into the groove 48.

45 50 is a shoulder on the valve which abuts 45 against the valve thimble 7 when the valve is in the position shown in Fig. 2.

49 is a series of holes through the shoulder 50.

50 23 is a radial surface on the valve, due to the difference in diameters J and K.

22 is a lip on the valve, whose interior closely fits diameter K on the valve block.

17 is a radial surface on the valve, due to the difference in diameters I and J.

14 is a radial surface on the valve, due to the difference in diameters H and I.

39 is a groove on the interior of the valve.

60 39^a is a series of openings through the wall of the valve into the groove 39.

11 is an annular chamber in the valve thimble adapted to be closed by the valve and valve block.

55 15 is an annular chamber between the

valve and valve block, due to the differences in diameters H and I and which may be enlarged by grooving the interior of the valve as shown.

18 is an annular chamber between the 70 valve and valve block, due to the differences in diameters I and J.

The rear end of the cylinder is bored to closely fit the outside of the thimble at 31^a.

26 is an open space between the cylinder 75 and the valve, and communicates with the atmosphere through a series of ports 27.

On the outside of the cylinder are formed a number of teeth 42.

45 is a dog having teeth 45^a which mesh 80 into the teeth 42. The dog 45 is fitted into a recess in the handle 1, as shown in Figs. 1 and 9 and is held in place by the screw 43.

46 is a hole in the screw 43, through which a split pin may be inserted to prevent the 85 screw from turning.

44 is a washer of yielding material (preferably such as the well known and so called verona nut lock) which holds the dog against the handle under tension, to prevent 90 movement and consequent wear on the teeth 42 and 45^a, when the hammer is in operation. The function of the dog is to lock the handle to and prevent its unscrewing from the cylinder.

The operation of my device is as follows: Fluid pressure is admitted to the annular chamber 3, through the main admission port 2, and enters the annular groove 10 through the series of ports 8; pressure also enters the 100 annular chamber 15, between the valve and the block, through the ports 6, 9 and 16; consequently the inside of the valve block and cylinder and the annular chamber 15 are under pressure when the throttle valve (not 105 shown) is open.

At the beginning of the forward stroke, the valve being in its forward position as shown in Fig. 1, the piston 32^a will be at, or near, the extreme rear end of the cylinder bore, preferably about 1/2" 110 from the handle, which forms the rear cylinder head; when the valve is in its forward position, fluid pressure entering through the small orifice 6^a moves the piston forward, in the direction indicated by the arrow, until it 115 passes the series of ports 12, when fluid pressure passing from the groove 10 into the chamber 11, thence through ports 12, into the cylinder bore, forces the piston forward at high velocity. As the piston moves forward the fluid in the front end of the cylinder exhausts through ports 34, 35, 36 and 37 into the groove 38 and thence through the holes 39^a into the chamber 26 and thence to the atmosphere through the openings 27. 120

When pressure acting on the radial surface 13^b of the valve is thus tending to hold the valve in its forward position, there is an opposing pressure on the smaller annular surface 14, but which is not sufficient to over- 125 130

come the force acting against 13^b. When the piston on its forward stroke passes the ports 25, pressure is admitted to the groove 24, and acts against the annular surface 23, which tends to force the valve rearwardly.

The radial surfaces 13^b, 14, 17 and 23 are so proportioned that the combined areas of the radial surfaces 14 and 23 are less than the radial surface 13^b. Consequently, the valve will remain in the position shown in Fig. 1 after the piston has passed beyond ports 25, and pressure admitted against the radial surface 23. When the valve has advanced beyond opening 30, pressure is admitted to the chamber 18, through the ports 21^a, 21 and 20, which acts against the radial surface 17 and tends to force the valve rearwardly, and the various parts are so proportioned that the combined areas of the radial surfaces 14, 17 and 23 are greater than the radial surface 13^b; the valve will consequently be thrown rearwardly into the position shown in Fig. 2. The groove 10 will now be sealed by the rear end of the valve and pressure will cease to pass from the groove 10 into the rear end of the cylinder, save through the very small port 6^a, while the fluid in the rear end of the cylinder will exhaust through the ports 25 into the groove 24, thence past the front end of the valve into the chamber 26, and thence through the ports 27 into the atmosphere, thus relieving pressure on areas 13^b, 17 and 23; the valve being held in this position by pressure on the radial surface 14. At the same time the groove 38 in the valve block is sealed off from communication with the chamber 26, as indicated in Fig. 2, while pressure from the chamber 15 enters the front end of the cylinder through ports 40, 36^a, 36, 35 and 34, to drive the piston rearwardly, or in the direction indicated by the arrow in Fig. 2. When the valve strikes the thimble, at the end of its rearward stroke, it is moving at high velocity and would have a tendency to rebound several times were not means provided to prevent this action. In my earlier experiments I found that this rebound was at times sufficient to alternately open and close the various admission and exhaust ports several times in rapid succession, before coming to rest, thus interfering with the proper action of the piston and rendering the performance of the device erratic and unreliable. To obviate this action I provide the radial surface 14 on the valve, which is always under pressure of fluid entering ports 6, 9 and 16. The force thus supplied, tending to hold the valve in its rearward position (Fig. 2) prevents the rebound, and moreover, holds the valve in position after pressure against radial surfaces 17 and 23 has been relieved by the exhaust of fluid through ports 25 and 27.

When, while moving rearwardly in the di-

rection indicated by the arrow in Fig. 2, the piston covers the ports 25, the fluid in the rear end of the cylinder is compressed and pressure builds up against the surface 13^b on the rear end of the valve, until it overcomes the constant pressure on the annular surface 14; the valve is consequently thrown into the position shown in Fig. 1, and the parts are so proportioned that the valve will be thrown forward in time to admit pressure to the rear end of the cylinder in time to catch the piston before it strikes the rear cylinder head. Fluid pressure is admitted to the cylinder bore through 6^a for the purpose of assisting the act of compression just described, and thus throwing the valve more quickly than would be done by simply compressing the fluid in the rear end of the cylinder. The cycle of operations is thus completed and is repeated in rapid succession. The lip 22 on the forward end of the valve is longer than the width of groove 10, and consequently the valve, when moving rearwardly, closes admission from port 10 before opening exhaust from groove 24 giving what is known as lap in steam engine practice. The advantage of this lap is two fold. It insures the positive closing of admission port 10 before exhaust opens from groove 24, thus avoiding waste of fluid, and conduces to higher efficiency by causing the fluid driving the piston forward, to act expansively for the interval of time during which the valve is moving the length of the lap.

My object in providing the four radial surfaces 13^b, 14, 17 and 23, against which pressure acts to manipulate the valve, is as follows: When, with the valve in position, shown in Fig. 2, the piston in moving rearwardly passes port 30, fluid pressure forcing the piston rearwardly enters ports 30, 21^a, 21 and 20 and acts against radial surface 17 and if the aggregate areas of radial surface 17 and 14 were greater than the area of surface 13^b the valve would not be thrown into position (Fig. 1) even though compression should build up to initial pressure. Consequently the piston would be forced rearwardly until it passed the ports 25, whence the pressure in the front end of the cylinder would exhaust. Should, however, the piston be so long as to cover ports 25 when resting against the rear cylinder head (a condition sometimes desirable in practice), the piston would be forced and held against the rear cylinder head and further operation cease. I therefore find it preferable to make the various areas of the annular surfaces 13^b, 14, 17 and 23 such that the area 13^b is greater than the combined areas of 14 and 23, or the combined areas of 14 and 17, though, for reasons explained above, the area 13^b must be less than the combined areas 14, 17 and 23.

A slight amount of leakage between cer-

4

tain parts of the valve and valve block of pneumatic tools of this class will seriously interfere with the operation of the tool. For example—when the valve is in the position shown in Fig. 2, leakage passing from the groove 10 and between the valve and thimble, might enter the chamber 11 and pass thence through ports 12, into the rear end of the cylinder, with the result that after the piston passes ports 25, on its rearward stroke, compression will build up more rapidly than desirable and stop the piston before it has reached the proper limit on its rearward stroke, thus shortening the piston stroke, and correspondingly reducing the force of its blow. In order to prevent this leakage from entering the rear end of the cylinder, I provide the arrangement shown in detail in Fig. 11, consisting of the annular groove 54^a, the small ports 54, a groove 53, the small ports 52, groove 57 and a series of small holes 49 in the valve. With this arrangement, leakage from the groove 10 in the thimble, will, instead of passing into the rear end of the cylinder, enter the groove 54^a and pass thence through ways 54, 53, 52, 57, 51 and 49 into the space 26 and thence into the atmosphere through the ports 27.

When the valve is in the position shown in Fig. 1, ports 52 are sealed by the close fit of the valve in the thimble at 13^a, thus preventing wasteful leakage from chamber 11 through 54^a, 53 and 52. Pressure from the chamber 15 is prevented from leaking into ports 12 by the groove 56, from which such leakage passes through the small ports 55 into the groove 57 and thence through 49 to the atmosphere as before. By thus preventing leakage from entering the rear end of the cylinder a constant length of stroke is insured.

When the piston covers port 30, on its forward stroke, the valve (being in position shown in Fig. 1), might be thrown prematurely by leakage from constant pressure chamber 15 into chamber 18, thus admitting pressure against the radial surface 17. To prevent such action I provide the groove 48 in the interior of the valve and the openings 47, which are in constant communication with the atmosphere by way of the chamber 26 and ports 27. By this arrangement whatever leakage may pass from constant pressure chamber 15 toward chamber 18 is shunted to the atmosphere. I also prevent leakage from passing from groove 38 (which is under pressure when the valve is in position shown in Fig. 2), into the chamber 18, by the groove 39 in the valve, which permits leakage from 38 to pass through the series of holes 39^a in the valve, into chamber 26 and thence through exhaust ports 27. For convenience I will hereinafter refer to the grooves 39, 48, 56 57 and

54^a and the portions of the block contiguous thereto, as leakage zones, while I will refer to the portions of the valve and valve block which are subject to fluid pressure, either constantly or intermittently, as pressure zones.

It is evident that when the valve moves from the position shown in Fig. 2 to that in Fig. 1 the fluid in the chamber 18 would be compressed, were it not allowed to escape through ports 20, 21 and 30, a condition which occurs in certain sizes of hammers, wherein the piston is so long that it fails to uncover the port 30 when at the extreme end of its rearward stroke. A perfectly fitting valve under these conditions would not be moved to the extreme forward position, as shown in Fig. 1 by the pressure on 13^b, which would seriously interfere with the operation of the device; I therefore provide one or more small leakage holes 19, to prevent compression taking place in this way; the leakage holes 19, being so small relatively to the size of the ports 30, 21^a, 21 and 20, as not to interfere with the action of the air against the radial surface 17 to throw the valve, after the piston has passed port 30 when moving forwardly.

In pneumatic hammers of this general design the piston and snap are thrown into violent vibration at the instant of contact, with the result that the cylinder bore is worn and enlarged at the front end, as indicated in dotted lines 32^b, as is also the fit of the snap in the cylinder. The resulting leakage due to such cylinder wear of fluid pressure admitted through ports 40, 36^a, 35 and 34 for driving the piston rearwardly, becomes, in time, so great as to seriously impair the efficiency of the tool. It is common practice to remedy this condition by heating the cylinder and closing in the worn part under a hammer and then reaming the cylinder bore and the part of the cylinder wherein the snap is inserted, to the proper size. In order that this operation of re-reaming may be performed repeatedly, it is desirable that the thickness of metal between ports 35 and the cylinder bore be as great as practicable; while in order to reduce weight, all dimensions of tools of this class are made as small as possible, consistent with proper strength. I consequently make the diameter K, on the valve block, such that the inside edges of ports 36 are quite close to the cylinder bore at the point 36^b, and drill the port 35 at an angle to the axis of the cylinder bore, thus acquiring a sufficient thickness of metal between port 35 and the cylinder bore at the front end to permit of drawing in and reborning the cylinder a number of times.

I claim:

1. In a pneumatic hammer a valve having a first radial surface subject to con-

- stant pressure tending to throw the valve in a certain direction, a second radial surface subject to intermittent pressure tending to throw the valve in the same direction, 5 a third radial surface subject to intermittent pressure tending to throw the valve in the same direction, and a fourth radial surface subject to intermittent pressure tending to throw the valve in the opposite direction; 10 the area of the fourth radial surface being greater than the sum of the first and second radial surfaces, but less than the sum of the first, second and third radial surfaces.
2. In a pneumatic hammer a valve having a radial surface under constant pressure, a second radial surface under pressure intermittently admitted from the cylinder bore, a third radial surface under pressure intermittently admitted from the cylinder bore, all of said pressures tending to force the valve in one direction, and a fourth radial surface under pressure intermittently admitted from the main supply tending to force the valve in the opposite direction; the 25 area of said fourth radial surface being less than the combined areas of the other three.
3. In a pneumatic hammer a valve having a radial surface subject to constant pressure and a second radial surface subject to pressure intermittently admitted from the cylinder bore of the hammer, said pressures tending to force the valve in one direction, and a third radial surface, subject to pressure intermittently admitted through the main supply and tending to force the valve in the opposite direction, said third surface being greater than the combined areas of the other two.
4. In a pneumatic tool a valve block, a valve slidingly fitting the exterior of the valve block, a thimble fitting the peripheral exterior of the valve block and also the peripheral exterior of the valve, a port in the 45 thimble to which fluid pressure is constantly admitted while the tool is in operation, said port being sealed by the valve when the valve is at one end of its stroke, and being open to communication with the interior of the cylinder when the valve is at the other end of its stroke.
5. In a pneumatic tool a cylinder, a valve block, having its interior of the same diameter as the cylinder bore, means for holding the bore of the valve block in axial alinement with the cylinder bore, said valve
- block having four diameters on its exterior and a valve having four diameters on its interior said diameters in valve corresponding to and slidingly fitting the exterior diameters of the valve block. 60
6. In a pneumatic tool a cylinder, a hollow valve block secured in axial alinement with the cylinder bore, a piston slidingly fitting the hollow interior of the valve block 65 and the cylinder bore, a valve slidingly fitting four diameters on the exterior of the valve block, and a thimble slidingly fitting a portion exterior of the valve.
7. In a pneumatic tool a valve block having four diameters, a valve having four corresponding and slidingly fitting diameters, said valve having four radial surfaces, fluid pressure acting constantly on one of said radial surfaces and intermittently on the other said radial surfaces. 70
8. In a pneumatic tool a valve block having four diameters on its exterior and a valve having four diameters on its interior said diameters on valve, corresponding to and slidingly fitting said diameters on the valve block.
9. In a pneumatic tool a valve having opposing radial pressure areas, a valve block slidingly fitting the valve, a leakage zone 85 on the valve and block and a pressure zone on the valve intermittently subject to pressure and adjacent to said leakage zone.
10. In a pneumatic tool a valve block, a valve having opposing pressure areas slidely fitting the valve, a pressure zone formed by the valve and block, and a leakage zone adjacent to the pressure zone. 90
11. In a pneumatic tool a valve having a radial surface intermittently exposed to fluid pressure, and a leakage zone on the valve on each side of said radial surface. 95
12. In a pneumatic tool a cylinder having one or more longitudinal ports in the wall of the cylinder, said port or ports being farther from the cylinder bore at the forward end of the cylinder than at the rearward end. 100
13. In a pneumatic tool a cylinder having a cylinder bore, a longitudinal port in the wall of the cylinder, the axis of said port being at an angle to the axis of the cylinder bore, said angle being such that the thickness of wall between the cylinder bore and port is greater at the front end than at the rear end of the cylinder. 105

FRANK M. FABER.
